(57) **CLAIM**

The ornamental design for a glass drop, as shown and described.

DESCRIPTION

FIG. 1 is a front view of the glass drop, with the back view being a mirror image of FIG. 1 in accordance with the present invention;

FIG. 2 is a left side view of the glass drop in accordance with the present invention;

FIG. 3 is a right side view of the glass drop in accordance with the present invention;

FIG. 4 is a top view of the glass drop in accordance with the present invention; and,

FIG. 5 is a bottom view of the glass drop in accordance with the present invention.

Any dash lines depict environment and are not part of the claimed design. In addition, the stippling shown in the drawing is for shading purposes, and does not form a part of the claimed design.
